Primary Examiner — Rosemary K Tarcza

(57) **CLAIM**

The ornamental design for an energy storage power supply, as shown and described.

DESCRIPTION

1. Energy storage power supply

1.1 : Perspective

1.2 : Perspective

1.3 : Front

1.4 : Back

1.5 : Left

1.6 : Right

1.7 : Top

1.8 : Bottom

The key points of the design product: shape of design; the broken lines in the figures depict portions of the energy storage power supply that form no part of the claimed design.
